DRIVING MECHANISM FOR MACHINE TABLES

Ladislaus Robaczynski, Brooklyn, N. Y.

Application May 26, 1943, Serial No. 488,520

3 Claims. (Cl. 74—27)

This invention relates to new and useful improvements in driving mechanisms for the tables of surface grinders and similar machines of the type in which a work carrying table is reciprocated with relation to a tool which performs operations upon the work carried by said table.

One object of the present invention is to improve the construction and mode of operation of such driving mechanisms more particularly with respect to the manual operation thereof.

It is another object of the invention to provide a novel construction which eliminates all shocks and jars incidental to the reversing of the direction of travel of the work supporting table, thus reducing to a minimum, the vibration inherent in machines of this type as generally constructed.

It is a further object of the invention to provide a novel combination power actuated and manually operated table driving mechanism in which that portion of the mechanism which is power actuated may be operatively disconnected with the table when it is desired to operate the same manually.

The invention has been herein illustrated as embodied in a surface grinding machine but it is to be understood that it is not to be limited to such machines since it is applicable to machines of any type in which it is desirable to operate a work supporting table either by hand or power.

In the accompanying drawings,

Figure 1 is a horizontal sectional view of a surface grinding machine illustrating the improved mechanism embodied therein and its relation to the several elements of a conventional driving mechanism for such machines.

Figure 2 is a view in elevation partly broken away and partly in section taken substantially on the line 2—2 of Figure 1.

Figure 3 is a fragmentary sectional view taken substantially on the line 3—3 of Figure 2, and;

Figure 4 is a distended perspective view illustrating the detail construction of a clutch mechanism employed in connection with the driving mechanism.

Referring to the drawings by reference character, 10 designates the frame of the machine.

The frame 10 is preferably in the form of a housing, rectangular in cross sectional form and the front wall thereof is designated 11.

Two trackways 13 extend from front to rear of the top wall of the frame and slidably mounted upon these trackways 13, there is a saddle 14, provided upon its under face with tracks 15 for sliding engagement with the trackways 13.

Extending from left to right of the top face of the saddle 15 there are two trackways 16, one of which is illustrated in Figure 2 of the drawings.

Slidably mounted in the trackways 16 for reciprocating movement there is a work carrying table 17, the under face of which has tracks 18 for slidably mounting the table in the trackways 16, heretofore mentioned.

10 The saddle 14 serves to move the table and the work carried thereby intermittently with respect to a grinding wheel or other tool to present surfaces thereof successively to the tool by a mechanism not herein illustrated since it forms no part of the present invention.

15 The work supporting table is, during operation of the machine, reciprocated constantly relative to the grinding wheel or tool, and it is the mechanism for operating the work supporting table which forms the subject matter of this application.

20 Upon the exterior of the rear wall of the frame 10, there is a housing 19 and mounted within this housing, there is a motor 20. Mounted upon the shaft of the motor 20 there is a driving pulley 21.

25 Mounted in the rear wall of the frame 10 in bearings 24 there is a shaft 25 which carries a driven pulley 23 upon its outer end and a gear 26 upon its opposite or inner end. A belt 22 passes around the pulleys 21 and 23 and serves to drive the latter and the shaft 25.

30 Meshing with the gear 26 there is a gear 27. This gear is carried by a shaft 28 which is mounted at one end in a bearing 29 upon the inner face of the rear wall of the frame 10. The opposite end of the shaft 28 is mounted in a bearing 30 mounted in a bracket 31 which extends inwardly from the right hand side wall of the frame 10. This end of the shaft 28 extends slightly beyond the bearing 30 as at 32 and carries the gear

35 33 of a conventional automatic reversing mechanism 34 which operates to reverse the direction of rotation of the table driving gear to impart to the work supporting table, 17, the reciprocating motion, heretofore mentioned.

40 The shaft 37 of the automatic reversing gear 34 is mounted in bearings 35 in the inner ends of two brackets 36 which extend inwardly of the front wall 11 of the frame 10.

45 The shaft 37 has an extension 38 which is mounted in a bearing 39 in a bracket 40 which also extends inwardly of the front wall 11 of the frame 10 and this extension 38 carries upon its free end, a bevel gear 41.

50 55 Mounted in the front and rear walls of the

frame 10 as at 42 and 43 respectively there is a long cylinder gear 44 the forward end of which is operatively connected with a gear 45. This gear meshes with and is driven by a small gear 46 which latter gear, since it forms the means for driving the gear 45 and the cylinder gear 44 when operated either manually or by power, will be hereinafter referred to throughout the specification and claims as the driving gear.

Carried by the under face of the table 17, see Figure 2, there is a rack bar 47 and meshing with the rack bar 47 there is a gear 48. This gear 48 is mounted in lug bearings 49 depending from the under face of the saddle 14. The gear is positioned in an opening 50 in the saddle, indicated by dotted lines in Figure 2 and as also illustrated in said figure, the gear 48 meshes as at 51 with the cylinder gear 44.

By this construction, as the driving gear 46 is operated, either manually or by power, the gear 45 will drive the cylinder gear 44 which in turn will drive the gear 48 to operate the work supporting table 17 through the medium of the rack 47.

Having thus described the manner in which the work supporting table is operated by the driving gear 46, the manner in which the driving gear 46 is power operated by the automatic reversing gear 34 and also the manner in which it is operated manually and independently of the said automatic reversing gear will now be described.

The driving gear 46 is mounted upon a shaft 55, see Figure 3, to which it is operatively connected by a set screw or the like 56. This shaft 55 is mounted in a bearing 57 in a bracket 58 which extends inwardly from the left hand side wall of the frame 10, see Figure 1.

Referring again to Figure 3, the forward end of this shaft extends through an opening 59 in the front wall 11 of the frame 10 and this forward end is formed with an axially extending recess 60.

The reference character 61 designates a crank which has a shaft extension 62 which is adapted to project into and have sliding movement in the axial recess 60 of the shaft 55. The shaft extension 62 has an intermediate portion 63 of reduced diameter which construction provides two shoulders 64 and 65.

Sliding movement of the shaft extension 62 relative to the shaft 55 is limited by means of a screw or the like 66 carried by the shaft and extending into the space between the shoulders 64 and 65 of the shaft extension 62.

The crank 61 is provided with clutch teeth 67 which are adapted for engagement with clutch teeth 68 in the outer end of the shaft 55 for operatively connecting the crank 61 to the shaft, thereby to rotate the latter.

The shaft 55 is provided with a reduced portion 69 and a reduced screw threaded extremity 70. A clutch member 71 is loosely mounted upon the reduced portion 69 of the shaft 55 and is retained thereon by means of a sleeve 72 which in turn is retained on the shaft 55 by a washer 73 and a nut 74 which latter has threaded engagement with the threaded portion 70 of the shaft 55.

Extending forwardly of the shaft 55 from the clutch member 71, there is a sleeve-like extension 75 which has a threaded end portion 76. The threaded end 76 of the sleeve-like portion 75 of the clutch member 71 extends to and abuts with the shoulder 77 formed by the reduced portion 69 of the shaft 55.

By this construction, it will be apparent that 75

the clutch member 71 and the sleeve 72 are retained in position against movement longitudinally of the shaft 55 by the washer 73 and the nut 74.

5 The sleeve 72, heretofore mentioned, is provided with an internal keyway 78, see Figure 4, for the reception of a key 79, shown in dotted lines in Figure 3, which construction serves to connect the sleeve operatively with the shaft 55.

Slidably mounted upon the sleeve 72 there is a clutch collar 80. This clutch collar 80 is operatively connected to the sleeve 72 by a key 81 which engages in keyways 82 and 83 respectively in the sleeve 72 and the clutch collar 80.

15 The clutch collar 80 has an annular channel 84 and clutch teeth 85 which are adapted for meshing engagement with clutch teeth 86 on the clutch member 71.

For moving the clutch collar 80 into and out of clutching engagement with the clutch member 71, a hand crank 85, see Figure 1, is provided. The hand crank 85 is secured to a shaft 86 by means of a set screw or the like 87 and the shaft 86 is connected to a disk-like member 88 which operates in an opening 89 in the left hand side wall of the frame 10.

20 Eccentrically disposed with respect to the member 88 and extending therefrom, there is an arm 90 the inner end of which projects into the annular channel 84 of the clutch collar 80.

25 The hand crank 85 is provided with an operating handle 91 which is provided with an extension 92 the inner end of which serves as a pawl for engagement with either of two recesses 93 and 94 to retain the hand crank in either position to which it may be moved. The pawl is retained in engagement with the recess in either position by means of a spring which tends at all times to move the pawl into recess engaging position.

30 From the foregoing it will be apparent that with the hand crank in the full line position in Figure 1, the clutch collar 80 will be disengaged with the clutch member 71. When, however, the hand crank is moved to the dotted line position in Figure 1, the clutch collar 80 will be moved into operative connection with the clutch member 71 by reason of the eccentric position of the arm 90 with relation to the axis of the shaft 86.

35 The reference character 100 designates a beveled gear which is loosely mounted for limited rotary movement upon the sleeve-like portion 75 of the clutch member 71.

40 As best illustrated in Figures 1 and 4, the hub portion 101 of this gear is provided with a flange 102 which has a cut out portion 103 forming two shoulders 104 and 105.

45 Projecting from the clutch member 71 there is a radially off-set lug 106 which has an axial tongue extension 107. This axial tongue extension 107 occupies a position within the cut out portion 103 of the flange 102 and is adapted to cooperate alternately with the shoulders 104 and 105 to operate the clutch member 71 and the shaft 55 in opposite directions when the clutch collar 80 is operatively connected with the clutch member 71.

50 The beveled gear 100 is retained in position upon the sleeve-like portion 75 of the clutch member by means of a friction disc or plate 110, a spider-like spring washer 111 and two nuts 112 and 113, the nuts having threaded engagement with the threaded portion 76 of the sleeve-like portion 75.

55 The degree of frictional engagement of the friction disc or plate 110 with the bevel gear 100

is determined by the tension under which the spider-like spring washer is placed by the nuts 112 and 113 thus providing for an adjustment of said frictional engagement by said nuts.

By reference to Figure 1 of the drawings, it will be noted that the beveled gear 100 is driven directly by the beveled gear 41 carried by the extension 38 of the shaft 37 and that during such time as the motor 20 is operating, the bevel gear 100 will be continuously driven.

It is also to be noted, however, that unless the clutch collar 80 is operatively connected with the clutch member 71, the shaft 55 will not be driven by power for the reason that the clutch member 71 and the beveled gear 100 are free to turn together upon the shaft.

Therefore, when the clutch member 71 is disengaged with the clutch collar 80, the shaft 55 is free for turning by means of the hand crank 61.

With the parts in this last described position manual operation of the shaft 55 by engaging the clutch teeth 67 with the clutch teeth 68 will operate the driving gear 46, the gear 45, the cylinder gear 44 and the gear 48 to operate the table 17 in either direction entirely independent of the power operating means and whether or not it is under motion by the motor 20.

If it is desired to operate the work supporting table 17 by power, it is only necessary to move the hand crank 85 from the full line position in Figure 1 to the dotted line position in said figure. Such movement of the hand crank 85 will throw the clutch collar 80 into clutching engagement with the clutch member 71 which is driven by the beveled gear 100 through the medium of either of the shoulders 104 or 105 and the tongue 107, depending upon the direction of movement of said beveled gear.

Rotation of the clutch collar 80 drives the sleeve 72 through the medium of the key 81, the sleeve 72 driving the shaft 55 through the medium of the key 79. Rotation of the shaft 55 drives the driving gear 46 which in turn drives the cylinder gear 44, through the medium of the gear 45, the cylinder gear 44 in turn driving the gear 48 to move the table.

As heretofore stated the reversing mechanism 34 is automatically operated in the conventional manner to drive the shaft 38 and the beveled gear 100 in opposite directions to effect reciprocation of the work supporting table under power, assuming of course, that the clutch collar 80 is operatively connected with the clutch member 71.

By reason of the fact that there is a certain amount of play or lost motion between the clutch collar 80 and the clutch member 71, which play or lost motion occurs each time the direction of rotation of the beveled gear 100 is reversed, a yielding coupling between the beveled gear 100 and the shaft 55 is provided.

For example, with the parts in the positions in which they are shown in Figure 1, upon starting the motor, the beveled gear 100 would be rotated, but the shaft 55 would not be driven since the clutch collar 80 is not operatively connected with the clutch member 71.

Upon starting the motor, assuming that the reversing mechanism is so positioned as to drive the beveled gear in a clockwise direction, the shoulder 104 will engage the tongue 106 of the clutch member 71 to rotate the latter also in the clockwise direction.

If now the clutch collar 80 be thrown into clutching engagement with the clutch member 71 to drive the work supporting table, in the man-

ner heretofore described by power, the shock incidental to throwing the load onto the beveled gear 100 will be relieved by a slipping of said beveled gear 100 relative to the sleeve-like extension 15 of the clutch member, this slippage being permitted by the friction disc or plate 110 and the spring washed 111.

Referring again to Figure 1, upon reversal of the direction of rotation of the beveled gear 100 to the counter-clockwise direction, the shoulder 104 passes out of engagement with the tongue 106 and the shoulder 105 moves into engagement therewith to rotate the clutch member 71 in the counter-clockwise direction.

During the slight interval between disengagement of the shoulder 105 with the tongue 106, the work supporting table would be at rest at the end of one of its movements.

As the shoulder 105 comes into engagement with the tongue 106, the shock incidental to throwing the load of the work supporting table upon the beveled gear 100 is relieved by a slipping of said beveled gear which slippage is permitted again by the friction disc or plate 110 and the spring washer 111.

It has been found in actual practice that the flexible coupling above described eliminates almost entirely the vibration and jar incidental to the reversal of direction of movement of the work supporting table and that machines so constructed will operate with a higher degree of efficiency in precision grinding than it is possible to attain with surface grinders as generally constructed.

It will also be appreciated that the present construction and arrangement of parts permits of manually operating the driving gear 46 entirely independent of its power operating means and also whether its power operating means be in motion or at rest.

This also is an important feature of this invention since in all surface grinding machines with which I am familiar, it is necessary to shut off the power in order to drive the work supporting table manually and in such machines the manual operating means includes also, the entire power operating gear train and the reversing mechanism.

Having thus described the invention, what I claim as new and desire to secure by Letters Patent of the United States, is:

1. In a manually and/or power operated driving mechanism, a rotatable shaft, a driving gear fast on said shaft, a manually operable element, means to engage said element with the shaft to rotate the shaft upon the manual operation of said element, said means being disengaged when said element is in an idle position, cooperative clutch parts, a power driven reversing gear, a lost motion connection between said reversing gear and the first of said clutch parts at one side of the gear, a torque actuated slip device interposed between said reversing gear and said first clutch part at the other side of the gear, and the second of said clutch parts being connected with said shaft so as to be moved axially thereof and to cause rotational movement thereto when engaged with said first clutch part and said reversing gear is in operation.

2. In a manually and/or power operated driving mechanism as set forth in claim 1, and manually operable means to retain the second clutch part engaged with or disengaged from the first clutch part.

3. In a manually and/or power operated driv-

ing mechanism, a rotatable shaft, cooperative driven and drive clutch parts, a sleeve loosely keyed on said shaft, means on said shaft which coacts with said sleeve to hold said driven clutch part on the shaft against axial movement with respect to the shaft and allowing it to turn with respect thereto, said drive clutch part being slidably keyed to said sleeve, a power driven gear loose on said driven clutch part, a lost motion connection between said gear and the driven clutch part at one side of the gear, a torque actuated friction slip device coacting with said driven

clutch part and the gear at the other side of the gear, manually operable means to retain the drive clutch part engaged with the driven clutch part for transmission of the power effort to the shaft 5 while the gear is in operation, and to disengage the drive clutch part to enable manual operation of the shaft, and manually operable means engageable with the shaft to rotate the shaft and capable of being disengaged from the shaft while 10 the shaft is being power driven as aforesaid.

LADISLAUS ROBACZYNSKI.
